APPARATUS FOR LOCKING IGNITION TIMERS

Filed March 29, 1928

UNITED STATES PATENT OFFICE

HARRY E. NORVIEL, OF ANDERSON, INDIANA, ASSIGNOR TO DELCO-REMY CORPORATION, OF DAYTON, OHIO, A CORPORATION OF DELAWARE

APPARATUS FOR LOCKING IGNITION TIMERS

Application filed March 29, 1928. Serial No. 265,756.

This invention relates to apparatus for preventing theft or unauthorized use of an automotive vehicle, and more particularly to key controlled apparatus for preventing the functioning of the ignition timer of the engine which propels the vehicle and for preventing access to the ignition timer in order to defeat the purpose of the theft preventing device. By means of the present invention I aim to simplify the construction of and reduce the cost of manufacture of anti-theft devices of the type referred to.

Further objects and advantages of the present invention will be apparent from the following description, reference being had to the accompanying drawings, wherein a preferred embodiment of one form of the present invention is clearly shown.

In the drawings:

Fig. 1 is a plan view partly in section of an ignition timer and showing a fragment of a flexible armor which encloses a key controlled movable member for disabling the ignition timer.

Fig. 2 is a longitudinal sectional view of a key operated mechanism for moving the timer disabling member shown in Fig. 1.

Fig. 3 is a sectional view on the line 3—3 of Fig. 1, and shows in addition thereto a sectional view of the ignition distributor.

Fig. 4 is a sectional view on the line 4—4 of Fig. 1.

Fig. 5 is a sectional view on the line 5—5 of Fig. 3.

Fig. 6 is a sectional view on the line 6—6 of Fig. 3.

The ignition timer to which the present invention applies comprises a cup-shaped housing or timer cup 20 which supports by screws 21 a breaker lever bracket 22 having ears 23 through which the screws 21 pass. The bracket 22 supports a stud 24 around which a breaker lever 25 and a stationary contact bracket 26 are concentrically pivoted. The lever 25 carries a rubbing block 27 adapted

to be engaged by cam 28 which is rotatably supported by the timer in any suitable manner not shown. The lever 25 carries a timer contact 29 engageable with a relatively stationary contact 30 carried by the bracket 26 which is clamped in adjusted position relative to the plate 22 by screw 31 which passes through an arcuate slot 32 and threadedly engages the bracket 22. A rivet 33 secures the rubbing block 27 to the lever 25 and also secures one end of a leaf spring conductor 34 to the lever 25. The other end of the leaf spring conductor 34 is attached to a terminal bolt 35 which is insulatingly supported by the housing 20. The conductor 34 urges the contact 29 towards the contact 30 and the rubbing block 27 toward the cam 28. Obviously rotation of the cam 28 causes the timer contacts 29 and 30 to be intermittently separated, and permits the spring 34 to intermittently close the contacts in order that electrical energy may be stored electro-magnetically by an induction coil not shown, and thus dissipated so that a sparking impulse will be produced.

The sparking impulses which are produced by the cooperation of the ignition timer described and a suitable coil not shown are distributed by a distributing segment 40 mounted on a rotor block 41 supported by and driven by the cam 28. The segment 40 rotates past distributing post 41 which are integral with sockets 42 embedded in the distributor head of molded insulating material 43. The head 43 carries a center cable receiving socket 44 electrically connected with a center button 45 engaged by a rotor button 46 connected by a leaf spring conductor 37 with the segment 40. As shown in Fig. 3 the distributor head 43 is supported by the timer housing 20 and is secured thereto in any suitable manner.

In order to prevent access to the ignition timer by a thief or unauthorized person, the circuit interrupter is covered by a cover plate 90.

50 received within the timer cup 20 and provided with a center opening 51 to permit the cam 28 to extend into the space within the distributor head 43. The cover plate 50 is 5 provided with downwardly extending lugs 52 and 53 provided with notches 54 and 55 respectively. The notch 54 is adapted to receive a stud 56 permanently attached to the housing 20. The lug 52 is removably attached to the housing 20 by a screw 57. It is apparent that upon removal of the screw 57 the cover plate 50 can be removed from the timer by first turning it so that lug 52 will move in the direction of the arrow 58 in Fig. 10 5 in order that the lug 52 will be clear of the stud 56.

In order to prevent removal of the cover 50 from the cover I provide a key actuated mechanism which will prevent the turning of 20 the plate 50 in the manner referred to and which will also disable the circuit interrupter by preventing the engagement of the timer contacts 29 and 30. This key actuated mechanism comprises a key receiving cylinder or 25 shaft 60 which is turned by the proper key and which is rotatably supported by key barrel 61 carried by a disc 62 permanently attached to a hard metal housing 63. The key shaft 60 operates a screw threaded member 64 which cooperates with a nut 65 attached to a wire 66. The nut 65 is prevented from turning by providing it with a flange 67 which is notched to receive a lug 68 extending from the disc 62. The wire 66 passes 30 through a swivelly jointed hard metal armor 70, its end joint 71 being swivelly connected with the housing 63 and the other end joint 72 being permanently connected with a hard metal sleeve 73 having a flange 74 permanently attached to a locking bolt member 75 which is slidably guided by recess 76 in the armor joint member 72. A spring 77 tends to urge the bolt 75 into the position shown in Fig. 3.

45 The bolt 75 occupies the position shown in Fig. 3 when the timer is unlocked and is in condition for operation to provide ignition for the engine. The shank portion 78 of the bolt 75 is slightly less in diameter than the 50 narrower part of the notch 55 which is included between the edges 55a of the lug 53. The enlarged portion 79 of the bolt 75 is greater in diameter than the distance between the edges 55a and is but slightly less 55 in diameter than the wider or circular part 55b of the notch 55. Therefore when the bolt 75 occupies the position shown in Fig. 3 the cover 50 may be turned in a counter clockwise direction as viewed in Fig. 1 in order that the lug 53 may be moved as indicated by the arrow 80 in Fig. 4 in order that the lug 53 may clear the bolt 75. But if the bolt 75 is moved toward the left as viewed in Fig. 3 so that its portion 79 will be received 65 by the notched portion 55b of the lug 53, the

cover 50 cannot be turned into position for removal from the timer.

When the portion 79 of the bolt 75 is moved into position for locking the cover 50 against rotation, a flange 81 provided by the bolt 75 will engage an arm 82 which extends from the lever 25, and will prevent the lever 25 from moving under the action of the spring 34 into such position as to cause the contact 29 to engage the contact 30. As viewed in Fig. 3, the arm 82 is U-shaped in cross section and one of its sides or branches 82a is attached to the lever 25 by the rivet 33. As shown in Fig. 6 the branch 82a of the arm 82 is bent over at 82b of the web portion 25a of the lever 25, the lever being also U-shaped or channel-shaped in cross section as viewed in Fig. 3. In this way a single rivet attaches the arm 82 to the lever 25 and the arm 82 is prevented from turning simply by bending a portion of it indicated at 82b against a portion of the lever 25. As shown in Fig. 4 the portion 82c of the arm 82 is provided with a notch 83 which receives the portion 84 of the locking bolt 75. This notch is of 90 course less in diameter than the flange 81 of the bolt.

To stop the engine by turning off the ignition, the car driver turns the lock shaft or cylinder 60 by a suitable key in a counter-clockwise direction as viewed in the direction of the arrow 60a in Fig. 2. This will cause the nut 65 to move toward the left in order to move the bolt 75 toward the left as viewed in Figs. 1 and 2. The portion 79 of the locking bolt 75 will move within the circular recessed portion 55b in the lug 53 of the plate 50 and the flange 81 of the bolt 75 will move against the portion 82c of the arm 82 in order to prevent the closing of the interrupter contacts 29 and 30. In this way the ignition is discontinued and the engine stopped and the cover plate 50 is locked in position so that tampering with the ignition timer is substantially interfered with. To turn on the ignition, the key cylinder 60 is turned in a clockwise direction, as viewed in the direction of the arrow 60a in Fig. 2, thereby permitting the spring 77 to be released in order to move the bolt 75 into the position shown in Fig. 3, so that the ignition timer is permitted to operate in the normal way and so that the cover may be removed in case it is necessary to obtain access to the timer mechanism.

In assembling the timer and theft preventing device the separate assembly of the parts shown in Fig. 2 is made and the end of the wire 66 and the joint 72 of the armor 70 are passed through the sleeve 73, the spring 77 being in position within the bore 76 of the part 72. Before the interrupter mechanism is located within the housing 20 the bolt 75 is placed within the housing 20 and then is screw threaded attached to the wire or 120

rod 66. After the interrupter has been assembled as shown, the bolt 75 is adjusted relative to the wire by turning the bolt in order that the parts 81 and 79 thereof will be properly located.

5 The armor joint member 72 is permanently attached to the sleeve 73 after the assembly has been made by forcing into notches 90 provided in the joint member 72 one or more lugs 10 or tangs 91 integral with the sleeve 73 and formed by partly shearing away portions of the sleeve.

10 While the form of embodiment of the present invention as herein disclosed, constitutes a preferred form, it is to be understood that other forms might be adopted, all coming within the scope of the claims which follow.

What is claimed is as follows:

20 1. Apparatus for locking an ignition timer comprising, in combination, a housing, a circuit interrupter in the housing, a cover for the housing and provided with a lug having a notch including narrow and wide portions,

25 a locking bolt having a shank portion receivable by both portions of the notch and having an enlarged portion receivable only by the larger portion of the notch whereby edgewise movement of the cover is prevented when the 30 enlarged portion of the bolt is received by the larger portion of the notch, means cooperating with the locking bolt and interrupter to prevent functioning of the interrupter, and key controlled means for operating the bolt.

35 2. Apparatus for locking an ignition timer comprising, in combination, a housing, a circuit interrupter in the housing, a cover for the housing and provided with two lugs extending into the housing and each having a 40 notch, parts carried by the housing and received by the notches of the lugs when the cover is turned relative to the housing, one of said parts being a locking bolt supported by the housing, means provided by the cover

45 and bolt for preventing the turning of the cover when the bolt is in a certain position, means cooperating with the locking bolt and interrupter to prevent functioning of the interrupter, and key controlled means for operating the bolt.

50 3. Apparatus for locking an ignition timer comprising, in combination, a housing, a circuit interrupter in the housing, a cover for the housing and provided with two lugs extending into the housing and each having a 55 notch, parts carried by the housing and received by the notches of the lugs when the cover is turned relative to the housing, one of said parts being a locking bolt supported by the housing, the cover lug which receives the locking bolt having its notch so shaped as to provide relative wide and narrow portions, the wide portion receiving only an enlarged portion of the locking bolt whereby the cover

60 65 is prevented from turning when the bolt is

in a certain position, means cooperating with the locking bolt and interrupter to prevent functioning of the interrupter, and key controlled means for operating the bolt.

4. Apparatus for locking an ignition timer 70 comprising, in combination, a housing, a circuit interrupter within the housing, and having a cam-operated movable member, means for preventing intermittent movement of the movable interrupter-member and including 75 a movable locking bolt, a cover for the housing, means cooperating with the locking bolt and cover to prevent turning the cover when mounted upon the housing, means for fastening the cover to the housing and requiring the cover to be turned before it can be removed, and key controlled means for operating the bolt.

5. Apparatus for locking an ignition timer 80 comprising, in combination, an interrupter 85 having a circuit breaker lever provided with an arm attached directly thereto, a locking bolt engageable with said lever arm to prevent movement of the lever to close and open the ignition circuit, a housing enclosing the 90 locking bolt and circuit interrupter, a cover for the housing, means cooperating with the locking bolt and cover to prevent removal of the cover when the bolt is in position to prevent functioning of the lever, and key controlled means for operating the locking bolt.

6. In a distributor, an interrupter, means for preventing the interrupter from closing, said interrupter and means being enclosed in 100 a metal casing, and a cover for said casing which is removable when said means is in a position to allow said interrupter to close, said cover and means having interengaging portions which prevent the cover being moved to a position from which it can be removed from the casing when said means is in a position to prevent the interrupter from closing.

7. The distributor according to claim 6 110 characterized by the distributor shaft extending through openings in said casing and cover, and a distributor brush carried by the portion extending through said cover.

8. The distributor according to claim 6 115 characterized by the distributor shaft extending through openings in said casing and cover, a distributor brush carried by the portion extending through said cover, and an insulating distributor case enclosing the whole.

9. In a distributor, an interrupter, a metal casing enclosing said interrupter and having an integral metal tube leading thereto forming a lateral passage, and means lying partly within said passage for rendering said interrupter inoperative, said means being separately assembled and inserted into said passage.

10. In a distributor, an interrupter, a metal 130 casing enclosing said interrupter and having

a lateral passage, and means lying partly within said passage for rendering said interrupter inoperative, said means being separately assembled and inserted into said passage, said means including a longitudinally movable member operable by a lock tumbler, and a flexible member connecting said member and the movable part of said means lying partly within said passage.

10 In testimony whereof I hereto affix my signature.

HARRY E. NORVIEL.
